UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING APPARATUS.

Application filed October 22, 1921. Serial No. 509,694.

My invention relates to mining apparatus. It has for its object to provide an improved mining machine and more especially an improved mining machine especially 5 adapted to operate on pitching seams. A further object of my invention is to provide an improved means adapted to be applied to a standard mining machine whereby such a machine may be controlled in its movement 10 up a pitch and whereby the pulling out of a jack or the like, which would otherwise result in the machine sliding down the pitch with resultant injury to the operator and damage to the machine and props, is rendered harmless. These and other advantages of my improved construction will, however, hereinafter more fully appear.

In the accompanying drawings I have shown for purposes of illustration two forms 20 which my invention may assume in practice.

In these drawings:—

Fig. 1 is a plan view of a mining machine constructed in accordance with one form of 25 my invention, the machine being shown in cutting position adjacent a face.

Fig. 2 is a side elevation of the form of 30 the construction shown in Fig. 1, the machine being shown moving up a pitch.

Fig. 3 is a detail view partially in section of the controlling mechanism shown in Figures 1 and 2.

Fig. 4 is a detail sectional view on line 4—4 of Fig. 3.

Fig. 5 is a detail sectional view similar to Fig. 3 and showing a modified construction of controlling mechanism.

In these illustrative embodiments I have shown a standard form of mining machine 40 which, while the invention is not limited thereto, is of the longwall type including a usual machine casing 1 carrying at one end thereof a pivotally mounted cutter bar 2 adapted to be laterally disposed to under- 45 cut a face as the opposite end of the machine is moved in advance thereof along the face under the action of a feed operating member 3 controlled by a usual control mechanism including a member 4 and propelling 50 the machine along a flexible feeding member 5, the feed operating member herein being shown in the form of a feed sprocket member and the flexible feeding member in the form of a chain, although it will be evi-

dent that any other form of propulsion 55 means may be used. It will also be understood that the cutter mechanism and the feed operating member are driven from a motor (not shown) carried in the machine casing and operatively connected to these 60 elements in a usual manner.

In my improved construction illustrated in Figures 1 and 2, a safety member, herein in the form of a flexible member or cable 6, is disposed between the machine and the 65 props when the machine is at the face, one end of the flexible member being connected at the top of the pitch and the other at the bottom to suitable abutments of such strength as to enable the entire weight of 70 the machine to be placed upon the member 6 should the abutment or jack to which the flexible feeding member 5 is connected, be pulled out, or the flexible feeding member break. In a preferred form of my invention 75 this cable 6 is disposed at such a height above the bottom as to be above the free end of the flexible feeding member which is fed out on the prop side of the machine by the feed operating member, the same preferably also being disposed at such a height as to bring it substantially in the plane of the 80 machine controlling mechanism, herein typified by the member 4. As shown, the member 6 also extends through a suitable clamp 85 8 at the prop side of the front end of the machine, which is carried on a bracket 9 in such a manner as to project slightly laterally into the path of the member 6. This clamp 8 in the form of my invention shown in Fig. 90 9 is in the form of a conical member having cable gripping surfaces 10 and longitudinal slots 11, and seated in a correspondingly conical bore 12 in an extension 13 on the bracket, the member 8 also being provided with a 95 flange 14 on its reduced end engaging with a shoulder 15 on the portion 13 when the member 8 is in released position, the member 8, however, normally being projected 100 into contact with the cable 6 by means of springs 16 seated in apertures 17 in the member 13 and acting between that member and the flange 14. Operatively associated with the flange 14 is also a horizontally disposed controlling member 18 pivoted at 19 105 at a point adjacent one of its ends on a vertical pivot on the front end of the member 9 and having on its outer end and preferably

adjacent the pivot, spaced extensions 20 engageable with the outside surface of the flange 14.

As a result of my improved construction 5 it will be observed that when the machine is moving up a pitch, the parts occupy the position illustrated in Fig. 3, the spring pressed member 8 being projected into clamp releasing position by the friction on 10 the cable 6 so that the machine may move freely relative to the cable 6 and along the member 5. When, however, the machine starts down the pitch, as for instance when the jack for the flexible feeding member 5 15 pulls out, the friction of the clamp on the cable causes the member 8 to move longitudinally in its bore 12 and thereby to clamp the machine to the safety cable 6. Further, it will be noted that whenever the operator 20 for any reason desires to move the machine down the pitch, this is readily accomplished by simply releasing the member 18 and letting the machine slip as desired under the constant control of that member.

25 In Figure 5 I have illustrated a modified form of the construction hereinabove described where it will be noted that the clamping member generally indicated at 8 in that figure is formed of a plurality of 30 parts 21 and 22, one of which, 21, is connected through a suitable toggle mechanism to the member 9, herein through a plurality of toggle links 23 pivoted in that member and the member 9, while the other, 22, is 35 normally projected into clamping position by suitable resilient means, herein in the form of a plurality of coiled springs 24 seated in an extension 25 on the member 9. In this construction extensions 26 are also 40 provided on the member 21 and engaged by the spaced extensions 20 on the member 18. The operation of this construction will evidently be the same in principle as that of the preceding construction, friction on the 45 cable 6 acting automatically to apply and release the clamp, while the operator may lower the machine down the pitch under control of the control member.

Through the use of my improved construction 50 it is found possible to operate with entire safety upon pitching seams of as high as 55 degrees wherein safe operation of the machine has heretofore been thought impossible due to the risk to the lives of the operators below the machine and the damage to the machine and props which would result 55 from the pulling out of the upper jack for the flexible feed member or the breaking of the latter. Further, it will be noted that 60 the control member is conveniently located so that an operator operating the usual control member 4 of the machine may readily also operate the control member 18. Attention is also directed to the fact that my 65 improved mechanism may be very cheaply

produced and applied to a standard machine without change in the latter machine and at a very small expense while the safety mechanism itself is of a rugged character well adapted to withstand long service.

While I have in this application specifically described two forms which my invention may assume in practice, it will be understood that these forms of the same are shown for purposes of illustration and that 75 the invention may be modified and embodied in other forms without departing from its spirit or the scope of the appended claims.

What I claim as new and desire to secure by Letters Patent is:

1. In a mining apparatus, a mining machine including feeding means, a stationary member relative to which said machine is movable, means for frictionally engaging said member automatically upon movement 85 of said machine in one direction, and means for releasing said engaging means during such movement.

2. In a mining apparatus, a mining machine including feeding means, a stationary member relative to which said machine is movable during feeding, and means cooperating with said stationary member in controlling machine movement comprising means normally gripping said member but 95 automatically released on feeding movement, and means for releasing said gripping means on movement in a direction opposite such feeding movement.

3. The combination with a mining machine having a feeding means, of a cable element and a cable gripping element, one of said elements being stationary and the other connected to said machine for movement therewith and said cable gripping element 105 comprising means permitting free relative movement during normal machine feeding but automatically operative to check relative movement in a reverse direction.

4. The combination with a mining machine having feeding means, of a cable element and a cable gripping element, one of said elements being stationary and the other connected to said machine for movement therewith and said cable gripping element 115 comprising means permitting free relative movement during normal machine feeding but automatically operative to check relative movement in a reverse direction, and means operative at will to cause said last 120 mentioned means to permit free opposite relative movement.

5. In a mining apparatus, a flexibly fed mining machine slidable on its bottom on a mine bottom and having a projecting cutter bar, a safety member, and means whereby said machine is connected thereto upon a rearward movement of said machine.

6. In a mining apparatus, a flexibly fed mining machine slidable on its bottom on a 130

mine bottom and having a projecting cutter bar, a safety member, and normally operative manually releasable means for connecting said mining machine to said member upon machine movement.

7. In a mining apparatus, a mining machine having a projecting cutter bar, feeding means connected to said machine to feed the same along a face, a safety cable, and clamping means connected to said machine and movable along said cable including normally operative cable gripping elements.

8. In a mining apparatus, a mining machine having a projecting cutter bar, feeding means connected to said machine to feed the same along a face, a safety cable, and clamping means carried on said machine and movable along said cable and including normally operative cable gripping elements releasable by an operator.

9. In a mining apparatus, a mining machine movable along a face and having a projecting cutter bar, a safety cable disposed parallel to the face, cable clamping means on said machine comprising a gripping member and means normally holding said member in contact with said cable, and a control member controlling said gripping member.

10. In a mining apparatus, a flexibly fed mining machine including a projecting cut-

ter bar, a safety cable disposed parallel with the path thereof, and clamping means on said machine engageable with said cable and including a toggle connected member and a 35 cooperating spring pressed member and a controlling member controlling the movement of one of said members.

11. In a mining apparatus, a flexibly fed mining machine including a projecting cutter bar, a safety cable disposed parallel with the path thereof, and clamping means on said machine engageable with said cable and including a toggle connected member and a 40 cooperating spring pressed member and a 45 controlling member controlling the movement of said toggle connected member.

12. In a mining apparatus, a flexibly fed mining machine slidable on its bottom on a mine bottom and having a projecting cutter bar, a safety member in the form of a flexible member extending substantially parallel to the path of machine movement, and means connected to said machine and engaging and moving freely along said flexible member 55 during forward machine movement operative upon a rearward movement of said machine to connect the latter to said flexible member in a manner to preclude substantial rearward movement.

In testimony whereof I affix my signature.
MORRIS P. HOLMES.
